(57) **CLAIM**

(22) Filed: **Feb. 28, 2013**

The ornamental design for a electrical coaxial connector for high-frequency signals, as shown and described.

(30) **Foreign Application Priority Data**

DESCRIPTION

Sep. 6, 2012 (JP) 2012-021514

FIG. 1 is a top plan view of an electrical coaxial connector for high-frequency signals showing my new design;
FIG. 2 is a front view thereof;
FIG. 3 is a bottom view thereof;
FIG. 4 is a rear view thereof;
FIG. 5 is a right side view thereof; a left side view is a mirror image thereof;
FIG. 6 is a front, top and right side perspective view thereof; and,
FIG. 7 is a front, bottom and left side perspective view thereof.
